LAND, MAINE, A CORPORATION OF MAINE.

WINDING-MACHINE.

1,087,367.

Specification of Letters Patent.

Patented Feb. 17, 1914.

Application filed July 5, 1912. Serial No. 707,824.

To all whom it may concern:

Be it known that we, ARTHUR I. HARVEY and WILLIAM MARCROFT, citizens of the United States, residing at Providence and Cranston, respectively, in the county of Providence and State of Rhode Island, have invented certain new and useful Improvements in Winding-Machines, of which the following is a specification.

10 Our invention relates to winding machines for winding thread and yarn into cops or bobbins for use in the shuttles of looms.

15 Our improvement consists particularly in providing means for automatically controlling the traverse of the thread-guide at the beginning of the winding to adapt the machine to wind several layers of yarn on the bobbin with a relatively short traverse before the winding of the main portion of the bobbin with the maximum traverse is commenced.

20 The object of our improvement is to provide a machine having a "bunch-building" attachment for performing the "bunch" winding at the beginning of the bobbin, the term "bunch" being generally used to designate the short section of yarn first wound on the naked bobbin and designed to coöperate 25 with the "feeler-devices" which control the weft, or filling-replenishing mechanism of automatic looms.

25 The invention is fully described in the following specification illustrated by the accompanying drawings, in which:—

30 Figure 1 is a longitudinal elevation of a winding machine showing our new device applied thereto, the main frame of the machine being illustrated in section to disclose the operating mechanism contained therein; Fig. 2, a plan view of the same; Fig. 3, a detail view of a portion of the stopping mechanism of the machine; Figs. 4, 5, 6 and 7, enlarged detail views of the 35 controlling device for the traverse-mechanism, illustrating the parts in progressive stages of their operation; Figs. 8, 9 and 10, detail views of the parts of the controlling device.

40 Our invention is shown as applied to a machine of the same general type as that described in U. S. Patents Nos. 940,489 and

946,831, granted Nov. 16, 1909, and Jan. 18, 1910, respectively, to S. W. Wardwell. The basic machine consists essentially of a rotating winding-spindle B and a reciprocating traverse-bar C, the latter arranged opposite the spindle, and adapted to carry the thread-guide G, which besides its movement with the bar is fed progressively outward thereon to build the cop in superimposed conical layers. The winding-spindle B is mounted in a bearing α in the main frame A of the machine and is rotated from the main driving-shaft E by means of skew-gears e, e' . The traverse-bar C slides in a quill-shaped bearing α' , which has an extension α^2 extending through a bore in the side of the frame A, and is reciprocated from a rocker-arm F mounted on the continuously-oscillated shaft D. Our new traverse-controlling device operates directly in connection with the arm F and is arranged to automatically adjust the point of connection of the traverse-bar C with the arm to vary the operative length of the latter and regulate the length of traverse of the thread-guide as more fully explained hereinafter.

45 The traverse-bar C is preferably constructed in two parts C' and C ^{2} , the main portion C' sliding in the bearing α' , as before explained, and the extension C ^{2} connected thereto at its outer end by a pin-and-slot coupling c. The outer end of the extension C ^{2} is mounted in a bushing c' which is swiveled in an outboard bearing j supported on a bracket J extending from the frame A. The coupling c allows the inner end of the extension C ^{2} to swing inward from the plane of the axis of the main portion C' of the bar, as shown in Fig. 2, while the outer end of the bar swings in the swiveled bushing c'. This arrangement is the same as that described in U. S. Patent 940,489, above referred to, and provides that the contact means carried on the traverse-bar, and arranged to feed the thread-guide along the winding-spindle, shall contact with the first layers of yarn wound on the bobbin α before the base of the cop is built up to its maximum diameter. The progression or contact-mechanism is arranged as now briefly described, a more comprehensive description being given in the patent just referred to.

The thread-guide G is preferably supported on a thread-guide holder or arm *g*, of bifurcated form, having two legs *g'*, *g''* terminating in bearings *g²*, *g²* surrounding the 5 bar *C²*. Between the bearings *g²*, *g²* is an internally threaded sleeve or nut *h* which carries a relatively thin disk *H* called the contact-wheel. The bar *C²* is formed with screw-threads *c²* extending approximately 10 half way around its circumference and a spring *h'* is secured to the guide-holder *g* with its end bearing on a flange *h²* of the nut *h*. The spring *h'* acts to normally press the nut *h* into position to engage its threads 15 with the threads *c²* on the bar *C²*, but the bore of the nut is of sufficient diameter to allow its threads to pass over those on the bar when the nut is pressed in the opposite direction against the force of the spring. It 20 will be seen that while the machine is operating the nut *h* is engaged with the threads on the bar *C²* so that the turning of the wheel *H* will feed the thread-guide along the winding-spindle, but by releasing the 25 nut from engagement with the threads on the bar the guide can be slid back to adjust it in position to begin the winding of a new bobbin.

Mounted on the end of the bar *C'* is a 30 "former" *K*, so termed because it acts to direct the movement of the contact-wheel *H* away from the winding-spindle during the building of the base or heel of the bobbin and therefore determines the form of the 35 latter. The former *K* has an arm *k* arranged with its edge *k'* at an angle to the axis of the winding-spindle and by adjusting the arm at different angles the taper of the base of the bobbin can be regulated. 40 Adapted to bear on the edge *k'* of the arm *k* is a follower-arm *g³* extending rearwardly from the thread-guide holder *g*. Sliding in a bore at the inner end of the bar *C²* is a spring-pressed plunger *c³*, adapted to bear 45 against the inclined face *c⁴* of the coupling-plate *c* and tending to normally hold the bar *C²* in position to aline its axis with that of the bar *C'*. The swinging movement of the bar *C²* is limited by its pin *c⁵* sliding 50 in the slot *c⁶* of the plate *c* and with the follower *g³* bearing on the former-arm *k* the end of the bar is held with the pin at the inner end of the slot as shown in Fig. 2. This provides that the contact-wheel *H* will 55 be maintained in close proximity to the surface of the bobbin or cop-tube at the beginning of the winding so that its periphery will contact with the first layers of yarn wound on the latter at the rearward end of 60 each stroke of the thread-guide. The contact of the wheel with the surface of the yarn, during the rotation of the winding-spindle, acts to turn the wheel to feed the thread-guide outward along the spindle in 65 the manner now well known to those versed

in the art. As the thread-guide feeds outward along the traverse-bar *C²* the follower-arm *g³* slides along the incline of the arm *k* and allows the contact-wheel to recede from the axis of the winding-spindle in accordance with the growth in diameter of the winding. As the follower *g³* reaches the end of the arm *k* the base of the bobbin or cop attains its maximum diameter and the bar *C²* assumes a position in alinement with the bar *C'*. Henceforth the two sections *C'* and *C²* of the traverse-bar *C* are reciprocated in the same plane, as one continuous bar, and the contact-wheel *H* engages the bobbin at the rearward end of each reciprocation at a 75 point on the base of its forward conical end. In this way the bobbin grows by longitudinal extension, the conical layers forming a substantially cylindrical body terminating in the tapered delivery end or nose. 80

The stopping-mechanism of the machine for arresting the rotation of the winding-spindle and the reciprocation of the thread-guide consists essentially of a rockable bridge-member *L* which is pivoted on suitable bearings in the frame *A* and extends across and above the shafts *E* and *D*. The inner end of the member *L* is mounted on a rod *l* secured in the inner side of the frame *A* and the outer end is formed with a socket *l'* which receives the end of an extension *L'* secured in place by the screw *l²*. The extension *L'* reaches through a bearing in the outer side of the frame *A*, and secured in a bore at its end is a rod *M* held by the set-screw *m*. The opposite end of the rod *M* passes through a bearing *m'* in the bracket *J* and is bent down to form a handle *M'*. 95

The skew-gear *e'* which is driven from the gear *e* is mounted free to turn on the winding-spindle *B* and is connected rotatively therewith by means of a clutch-member *N*, see Figs. 1 and 2. The clutch-member *N* is keyed rotatively with the spindle, but is free to slide thereon to carry its tapered face *n* into and out of engagement with the corresponding face *e²* of the gear *e'*. A coiled spring *n'* bearing against a collar *n²* tends to normally maintain the clutch-member *N* in engagement with the gear *e'* so that the winding-spindle is driven therefrom; and the clutch-member is released from the gear *e'* to arrest the rotation of the spindle by means of a lever *l³*. The lever *l³* is preferably formed as a part of the bridge-member *L* and extends upwardly therefrom with its end adapted to engage the beveled face of an annular flange *n³* formed on the clutch-member *N*. 100

Referring to Figs. 2 and 3, the rocker-arm *F* which reciprocates the traverse-bar *C* is formed with a double hub *f* mounted free on the shaft *D* and connected therewith by a clutch-block *O* secured on the shaft by a screw *o*. Preferably, the hub *f* is provided 105

with a key or spline f' adapted to engage a corresponding slot o' in the face of the block O and a coiled spring o^2 bearing against a collar o^3 tends to normally hold the hub f in engagement with the clutch-block. The hub f is disengaged from the block O by means of the bridge-member L which is formed with an overhanging portion l^4 having a face l^5 adapted to engage 10 with a tapered projection f^2 on the end of the hub f to slide the hub against the action of the spring o^2 , see Fig. 3. A double-ended spring l^6 , see Figs. 1 and 2, is secured to the top of the member L with its free ends l^7, l^7 reaching down adjacent the sides of the projection f^2 on the hub f of the arm F. The ends of the spring l^6 act to prevent excessive rocking movement of the arm F after its disengagement from the clutch-block O 20 and serve to hold the arm in such relation to the clutch-block as to insure the spline f' being engaged with the slot o' upon the release of the hub f from the member L.

Referring now to Figs. 4, 5, 6 and 7, the arm F is formed with a curved slot f^3 extending from its upper end to a point adjacent its hub. Connected to the main portion C' of the traverse-bar C by a pin c' is a link P carrying a stud p at its opposite end adapted to engage the slot f^3 . A coiled spring q fastened to an extension f^4 on the top of the arm F and secured to the link P at p' tends to normally maintain the stud p at the upper end of the slot f^3 , see Fig. 7. 30 By sliding the stud p down in the slot f^3 the operative effect of the arm F may be varied to shorten the extent of traverse imparted to the traverse-bar C and through the latter to the thread-guide G. At the commencement 40 of the winding of a bobbin the stud p is held at the lower end of the slot f^3 and will therefore move through an arc of relatively short radius when the arm F is oscillated, so that the thread-guide is reciprocated with 45 a relatively short traverse to build the "bunch" on the bobbin. When the "bunch" has been built up to the required diameter, or, more properly speaking, when a sufficient length of yarn has been wound 50 into the "bunch", the stud p is moved to the upper end of the slot f^3 and the traverse-bar C will then be reciprocated with the maximum extent of traverse to wind the full layers which form the main portion of the bobbin. The means for automatically controlling the position of the stud p in the slot f^3 will now be described.

Pivoted on a screw r screwed into the side of the arm F is a ratchet disk or wheel 60 R having an annular rim or flange r' on its inner face, see Figs. 8 and 9. The flange r' is interrupted by a slot or opening r^2 , one side of which is bent up in the curved lip r^4 . Referring to Fig. 10, the stud p is 65 formed with an extension or pin p^2 of

smaller diameter than its main portion to adapt it to enter the opening r^2 in the flange r' . When the disk R is turned to register the opening r^2 with the slot f^3 in the arm F, as shown in Fig. 4, the pin p^2 will pass 70 through the opening r^2 , and by turning the disk slightly the under side of the flange r' will engage the pin and retain the stud p at the lower end of the slot f^3 , as illustrated in Fig. 5. To release the pin p^2 from engagement with the flange r' the disk 75 R is rotated in the direction indicated by the arrow z , Figs. 4, 5, 6 and 7, until the slot r^2 again registers with the slot f^3 in the arm F. This rotation of the disk R takes place during the winding of the "bunch" 80 on the bobbin and is effected by the rocking motion of the arm F through means now described: Secured to the hub f of the arm F by a screw s is a flat-spring pawl S formed 85 with a hooked end s' adapted to engage the teeth r^3 on the ratchet-disk R to prevent movement of the latter in a direction opposite to that indicated by the arrow z . Pivoted on a stud t adjacent the end of the link P is a pawl T formed with a hooked end t' , also adapted to engage the teeth r^3 on the disk R. The hub of the pawl T is formed with a lug or abutment t^2 having a flat face t^3 see Fig. 10, against which the end of a 90 spring U bears. The spring U is preferably formed of flat spring-metal, bent in hairpin shape, and secured in position by a pin v held in the end of the link P and having a slot v' through which one end u of the spring passes. The tendency of the spring U is to hold the pawl T in the position illustrated 95 in Fig. 6 to adapt its end to engage the teeth r^3 on the disk R, while allowing the pawl to rock slightly to ride backward over the teeth. The turning of the ratchet-disk R in the direction indicated by the arrow z is accomplished by the upward and downward movement of the pawl T due to the 100 rocking movement of the link P on its pivot p , in relation to the arm F, as the latter is oscillated back and forth by the rocker-shaft D.

Referring to Fig. 3, it will be noted that the overhanging portion l^4 of the bridge-member L, which engages the projection f^2 on the rear end of the hub f , has a pin l^8 extending outward toward the projection. The pin l^8 is adapted to engage with a depression or groove f^5 in the top of the projection f^2 when the arm F is rocked into its forward position, see Fig. 7. The engagement of the pin l^8 with the groove f^5 takes place only when the arm F is disconnected from the clutch-block O, as shown in Fig. 3. 115 That is to say, during the operation of the machine the bridge-member L is in such position that its overhanging portion l^4 is raised free of the projection f^2 on the hub f , as shown 120 by dotted lines in Fig. 3, and consequently 125 130

the pin l^8 is out of range of the groove f^6 in the top of the projection. When the bridge-member L is rocked to stop the machine its overhanging portion l^4 is brought 5 down into engagement with the beveled edge of the projection f^2 , as shown by full lines in Fig. 3 and previously described, and the pin l^8 is carried into position to engage the groove f^5 . The object of this engagement of 10 the pin l^8 with the groove f^5 is to hold the arm F at the forward end of its stroke so that the traverse-controlling mechanism may be set in its initial position to start the winding of the "bunch" as more fully described 15 hereinafter. It is also to be noted that it is not necessary for the arm F to be in its forward position when the portion l^4 of the member L rocks downward in order to effect this engagement of the pin l^8 with the groove 20 f^5 . Should the movement of the arm F be arrested in any position other than that at the forward end of its stroke the projection f^2 can be swung over under the pin l^8 by simply 25 rocking the arm F forward. Such movement of the arm is effected manually by pulling the traverse-rod C outward through its bearing in the frame A. It will be observed that the forward edge of the projection f^2 is rounded off at f^6 to adapt the 30 pin l^8 to ride up onto the top of the projection and the inherent spring tendency of the pin causes it to drop down into the groove f^5 when the latter comes into alignment 35 with the pin.

35 The operation of the whole machine is as follows: Referring first to Figs. 1 and 2, we have here shown a wooden bobbin α of usual form applied to the winding-spindle B, but other forms of holders for the yarn, such 40 as paper cop-tubes, for instance, might be employed with equal effect. Figs. 1 and 2 illustrate the machine at the beginning of the winding and we have shown the traverse rocker-arm F at the forward end of its throw. It is obvious, however, that the machine will not always stop with the arm F in this position, nor is it necessary, because, before starting the winding the operator must set the bunch-building mechanism and 45 he is instructed to perform the following operations: The first step taken is to pull the traverse-bar C outward in the direction indicated by the arrow w , see Fig. 1, and if the arm F is in any other position than at 50 the forward end of its stroke it will be moved forward until the pin l^8 engages the groove f^5 in the projection f^2 of the hub f. This engagement of the pin and groove locks the arm F in its forward position, as shown 55 in Fig. 1. The operator now pushes the traverse-bar C backward in the opposite direction and, the arm F being held from movement, the stud p on the link P is forced down to the bottom of the slot f^3 . During 60 the time the machine is operating to wind

with the full traverse of the thread-guide the ratchet-disk R remains in the position illustrated in Fig. 4 with the opening r^2 of the flange r' in line with the slot f^3 of the arm F. The pin p^2 on the stud p will therefore pass through the opening r^2 , when the stud is pushed down in the slot f^3 , and lie under the flange r' . At this point the pawl T will engage one of the teeth r^3 on the disk R and hold the link P against the action of the spring q in the position illustrated in Fig. 4. The bunch-building mechanism is now set ready to wind the first layers of the bobbin with a short traverse, and the thread-guide G is next adjusted in its rearward position on the traverse-bar C and the yarn y threaded through it with its end secured to the bobbin α . 70 75 80

The operation of the machine is started by turning the handle M' which operates the bridge-member L to release its lever l^3 from the clutch-member N, it being understood that the member L is withheld from action by suitable detents not here shown. As the clutch-member N is released it is carried into engagement with the gear e' , 90 through the action of the spring n' , and the rotation of the gear imparts rotation to the winding-spindle B. Concurrently with the release of the clutch-member N, the projection f^2 is also released from engagement with the member L and the hub f of the arm F slides into position to engage the clutch-block O, under the influence of the spring o^2 . As the slot o' rocks into alignment with the 100 spline f' on the hub f the two are engaged and in this manner the arm F is connected to the rocker-shaft D and is oscillated thereby. The stud p is now at the bottom of the slot f^3 and the rocking movement of the arm 105 F is transmitted to the traverse-bar C through the link P to impart a relatively short traverse to the thread-guide G. The pawl T is now hooked under one of the teeth r^3 on the disk R to hold the end of the link 110 P in its lowermost position, as before described, and the first backward movement of the arm F will cause the link to rock slightly in relation to the arm. This causes the end of the pawl T to be moved upward around 115 the axis of the disk R and hence the disk will be rotated to a slight extent by the action of the pawl. Fig. 4 illustrates the arm F at the forward end of its first throw while Fig. 5 shows it at the rearward end and it 120 will be seen that in this latter position the disk R has been turned through a distance equal to the length of one tooth. This brings the end of the flange r' over the pin p^2 on the stud p so that the latter is held 125 at the lower end of the slot f^3 after the pawl T swings away from the teeth r^3 . The upturned lip r^4 on the flange r' is provided to insure that the pin p^2 will slide easily under the edge of the flange even if there 130

should be some play or looseness in the parts that hold the link P down at the beginning of the operation of the mechanism. At the next forward stroke of the arm F the pawl T is again engaged with the next tooth on the disk R and upon the rearward movement of the arm the disk is turned again to carry the rim r' still farther around on the pin p^2 . This action continues until the disk R has been turned through a complete rotation and the opening r^2 is again brought into alignment with the slot f^3 on the arm F . Fig. 6 illustrates the parts in the position they assume just previous to the completion of the rotation of the disk R . The pin p^2 is now held just under the rear edge of the flange r' and as the arm F moves backward into the position illustrated in Fig. 7 the disk R is turned sufficiently to bring the opening r^2 in line with the pin p^2 and the latter is released. The release of the pin p^2 allows the spring q to carry the stud p to the upper end of the slot f^3 and henceforth the arm F will act through the link to impart the full length of throw to the thread-guide. After the release of the pin p^2 the pawl T is carried away from the disk R and hence the latter is not turned farther, but is held by the pawl S with the opening r^2 in the flange r' in position to admit the pin p^2 when the mechanism is reset for winding a new bobbin.

Referring now to Fig. 2, it will be seen that while the stud p is at the bottom of the slot f^3 the arm F will act to reciprocate the thread-guide with a traverse of about one half the length of the full traverse illustrated by the layer y^2 . This causes the yarn to build up in the relatively short layers to form the "bunch" y' and the number of layers in the "bunch" is determined by the number of oscillations required to turn the disk R through a complete rotation. We have preferred to show our device arranged with sixteen teeth on the disk R , so that sixteen traverses of the thread-guide will take place before the "bunch" is completed, but it is obvious that a greater or less number of teeth might be provided so that more or less yarn would be wound into the "bunch." Furthermore, the ratchet might be made with very much finer teeth and means provided to adjust the pawl T to take one or a number of teeth at each movement of the arm F so that the "bunch" could be wound to contain various lengths of yarn as desired. After the "bunch" is completed on the bobbin the traverse-mechanism acts to reciprocate the thread-guide with the maximum extent of traverse to build the main portion of the bobbin with full length layers as before described; and after a bobbin is completed the parts of the controlling-device are in position to be reset for winding the "bunch" on the next bob-

bin. The resetting of the device is accomplished with two simple movements of the hand, as before explained, and requires no special skill or expertness on the part of the operator. Furthermore, the arrangement is so simple, and the mechanism so positive in action, that the device cannot get out of order and it is practically proof against damage through carelessness.

It is obvious that our new device might be applied to machines of different design from that here shown and described, or adapted for other arrangements of winding mechanism. For instance, the controlling-device for regulating the extent of the traverse with which the yarn is wound might be arranged to operate in connection with a traverse-mechanism for reciprocating the winding-spindle in respect to the guide instead of reciprocating the guide, itself.

Various modifications might also be made in the form and structure of the parts of our device without departing from the spirit or scope of the invention.

Therefore, without limiting ourselves to the exact arrangement shown and described, what we claim is:—

1. In a winding machine, the combination with the winding-spindle, of a traverse-bar adapted to be reciprocated in the direction of its axis with respect to the spindle, a thread-guide on said bar, means to feed said guide progressively along the bar during the reciprocation of the latter, means to cause the bar to be reciprocated with a relatively short traverse during a predetermined number of reciprocations to wind a "bunch" at the beginning of the bobbin, and means to cause the bar to be reciprocated with a relatively long traverse after the completion of the "bunch" to wind the main portion of the bobbin.

2. In a winding machine, the combination with the winding-spindle, of a traverse-bar adapted to be reciprocated in the direction of its axis with respect to the spindle, a thread-guide mounted on said bar, means to advance said guide progressively along the bar during the reciprocation of the latter, means to reciprocate the traverse-bar with two different extents of traverse, and controlling-devices co-operating with the reciprocating means to cause the bar to be reciprocated with the minimum extent of traverse during a predetermined number of reciprocations.

3. In a winding machine, the combination with the winding-spindle, of a traverse-bar, a thread-guide mounted on said bar, means to cause a relative longitudinal reciprocation between the spindle and bar, means to feed the thread-guide progressively along the bar during the winding, means to regulate the reciprocation of the traverse-bar to cause the yarn to be laid by the guide with a relatively short extent of traverse during

a predetermined number of reciprocations to build a "bunch" on the bobbin, and means to cause the guide to lay the yarn with a longer traverse to build the main portion of 5 the bobbin.

4. In a winding machine, the combination with the winding-spindle, of a traverse-bar adapted to be reciprocated in an axial direction with respect to said spindle, a thread-guide mounted on said bar, means to feed the guide progressively along the bar during its reciprocation, means to reciprocate the traverse-bar with a varying extent of traverse, controlling devices coöperating with 10 the reciprocating-means to cause the traverse-bar to be reciprocated with a relatively short traverse, and means actuated by the reciprocating-means after a predetermined number of reciprocations of the bar to cause 15 20 the thread-guide to be reciprocated with a longer traverse.

5. In a winding machine, the combination with the winding-spindle, of a traverse-bar adapted to be reciprocated in the direction 25 of its axis with respect to the spindle, a thread-guide mounted on said bar, means to feed the guide progressively along the bar during the reciprocation of the latter, means to reciprocate the bar with a varying extent of traverse, controlling-devices coöperating with said means to cause the bar to be reciprocated with a relatively short traverse, and means actuated by the reciprocating-means at each reciprocation of 30 35 the bar to operate the controlling-means after a predetermined number of reciprocations to cause the bar to be reciprocated with a longer traverse.

6. In a winding machine, the combination 40 with the winding-spindle, of a traverse-bar adapted to be reciprocated in the direction of its axis with respect to the spindle, a thread-guide mounted on said bar, means to feed the guide progressively along the bar 45 during the reciprocation of the latter, an oscillating arm for reciprocating the bar, means to cause the arm to reciprocate the bar with a relatively short traverse, and means operated after a predetermined number 50 of oscillations of the arm to cause the latter to reciprocate the bar with a longer traverse.

7. In a winding machine, the combination 55 with the winding-spindle, of a traverse-bar adapted to be reciprocated in the direction of its axis with respect to the spindle, a thread-guide mounted on said bar, means to feed the guide progressively along the bar during the reciprocation of the latter, 60 an oscillating arm for reciprocating the bar, means to cause the arm to reciprocate the bar with a relatively short traverse, devices operating to release said means after a predetermined number of reciprocations of the

bar, and means to cause the arm to reciprocate the bar with a longer traverse after the release of the first named means. 65

8. In a winding machine, the combination with the winding-spindle and thread-guide, of an oscillating member having a constant stroke, means on said member connected to reciprocate the guide therefrom, devices to maintain said connecting means at a point adjacent the axis of said member to cause the guide to be reciprocated 70 with a relatively short traverse to build a "bunch" at the beginning of the bobbin, and means operating at the completion of the "bunch" to immediately shift said connecting-means to the outer end of said member to cause the guide to be reciprocated 75 with a relatively long traverse to wind the main portion of the bobbin. 80

9. In a winding machine, the combination with the winding-spindle and thread-guide, of an oscillating arm for reciprocating the guide, means adapted to connect the guide with the arm at different distances from the axis about which the arm oscillates, means to retain the connecting-means at a point relatively near the axis of the arm during a predetermined number of reciprocations to wind a certain number of layers of comparatively short traverse for forming a "bunch" on the bobbin, and means to move the connecting-means away from the axis of the arm to cause the guide to wind the main portion of the bobbin with a longer traverse. 85 90 95

10. In a winding machine, the combination with the winding-spindle and thread-guide, of an oscillating arm for reciprocating the guide, means adapted to connect the guide at different points on the arm to vary the operative effect of the latter, means to maintain the connecting-means in position to cause the arm to reciprocate the guide with a relatively short traverse, and means to shift the connecting-means after a predetermined number of oscillations of the arm to cause the latter to reciprocate the guide with a longer traverse. 100 105 110

11. In a winding machine, the combination with the winding-spindle and thread-guide, of an oscillating arm for reciprocating the guide, means to connect the guide at different points on the arm to vary the operative effect of the latter, means to maintain the connecting means in position to cause the arm to reciprocate the guide with a relatively short traverse during a predetermined number of reciprocations, and means operated by the oscillation of the arm to shift the connecting-means to cause the arm to reciprocate the guide with a longer 115 120 125 traverse.

12. In a winding machine, the combination with a winding-spindle and thread-

guide, of an oscillating arm for reciprocating the guide, means to connect the guide at different points on the arm to vary the operative effect of the latter, means to retain said connecting-means in position to reciprocate the guide with a relatively short traverse, devices to operate said retaining-means to release the connecting-means after a predetermined number of reciprocations of the guide, and means to shift the connecting-means after its release by the retaining-means to cause the arm to reciprocate the guide with a longer traverse.

13. In a winding machine, the combination with a winding-spindle and thread-guide, of an oscillating arm for reciprocating the guide, means to connect the guide at different points on the arm to vary the operative effect of the latter, means to retain said connecting-means in position to reciprocate the guide with a relatively short traverse, means operated by the oscillation of the arm to actuate the retaining-means to release the connecting-means after a predetermined number of reciprocations of the guide, and means to shift the connecting-means after its release by the retaining-means to cause the arm to reciprocate the guide with a longer traverse.

14. In a winding machine, the combination with a winding-spindle and thread-guide, of an oscillating arm for reciprocating the guide, means connecting the guide with the arm and adapted to slide on the latter to vary the operative effect of its throw, a ratchet on the arm, means on the ratchet to retain the connecting-means at a distance away from the end of the arm, and means to operate the ratchet to release the connecting-means to allow the latter to be shifted to the end of the arm.

15. In a winding machine, the combination with a winding-spindle and thread-guide, of an oscillating arm for reciprocating the guide, means connecting the guide with the arm and adapted to be shifted on the latter to vary the operative effect of its throw, a ratchet on the arm, means on the ratchet to retain the connecting-means at a point adjacent the axis of the arm, and means actuated at each oscillation of the arm to operate the ratchet to release the retaining-means after a predetermined number of reciprocations of the guide.

16. In a winding machine, the combination with the winding-spindle and thread-guide, of an oscillating arm for reciprocating the guide, means connecting said arm with the guide, manually-operated means for adjusting the connecting-means on the arm to adapt the latter to reciprocate the guide with a relatively short traverse, and automatically-operated means for shifting the connecting-means immediately from one end

of the arm to the other after a predetermined number of oscillations of said arm to cause the latter to reciprocate the guide with a relatively long traverse.

17. In a winding machine, the combination with the winding-spindle and thread-guide, of an oscillating arm for reciprocating the guide, means connecting the guide with the arm and adapted to be shifted on the latter to vary the operative effect of its throw, a ratchet on the arm, means on the ratchet for retaining the connecting-means at a point adjacent the axis of the arm, a pawl actuated through the oscillation of the arm to operate the ratchet to release the retaining-means after a predetermined number of reciprocations of the guide, and means to shift the connecting-means on the arm after the release of the retaining-means to cause the arm to reciprocate the guide with the maximum extent of traverse.

18. In a winding machine, the combination with the winding-spindle and thread-guide, of an oscillating arm for reciprocating the guide, a link connecting the guide with the arm, means to adapt the link to slide on the arm to vary the operative effect of the latter, a ratchet on the arm, means to engage the ratchet with the link to maintain the latter in a position adjacent the axis of the arm, a pawl on the link adapted to be operated at each oscillation of the arm to move the ratchet to release the link, and a spring adapted to shift the link to the end of the arm after its release by the ratchet.

19. In a winding machine, the combination with a winding-spindle and thread-guide, of an oscillating arm for reciprocating the guide, a link connected to the guide with its end adapted to slide along the arm, a pin on the end of the link, a ratchet-disk formed with an annular rim adapted to engage the pin to maintain the link in its lowermost position on the arm, said rim having an opening to admit the pin, and means to turn the disk to release the pin through the opening after a predetermined number of reciprocations of the guide.

20. In a winding machine, the combination with the winding-spindle and thread-guide, of an oscillating arm formed with a radially-disposed slot, a link connected to the guide, a stud at the opposite end of the link adapted to engage the slot in the arm, means to retain the stud at the inner end of the slot during a predetermined number of oscillations of the arm, means to release the retaining-means, and a spring to carry the stud to the outer end of the slot after its release by the retaining means.

21. In a winding machine, the combination with the winding-spindle and thread-guide, of an oscillating arm formed with a radially-disposed slot, a link connected to

- the guide, a stud at the opposite end of the link adapted to engage the slot in the arm, means to normally maintain the stud at the outer end of the slot, means to retain the stud 5 at the inner end of the slot, and means operated automatically during the oscillation of the arm to release the retaining-means.
22. In a winding machine, the combination with the winding-spindle and thread-guide, of an oscillating arm, a link connected with the guide, means to connect the opposite end of the link to slide on the arm, a ratchet-disk rotatably mounted on the arm, a pawl to restrain said disk from rotating in 10 one direction, means on the disk adapted to hold the link at a point adjacent the axis of the arm, and a pawl on the end of the link adapted to engage the ratchet on the disk to rotate the latter during the oscillation of 15 the arm to release the link after a predetermined number of reciprocations of the guide.
23. In a winding machine, the combination with a winding-spindle and thread-guide, of a reciprocating traverse-bar for carrying the guide, an oscillating arm, a link connected with the traverse-bar, a stud at the end of the link adapted to slide on the arm, a pin projecting from said stud, a 20 ratchet-disk formed with an annular rim having an opening to admit the pin under the rim, and means to turn the disk through one complete rotation during a predetermined number of oscillations of the 25 arm to release the pin.
24. In a winding machine, the combination with the winding-spindle and thread-guide, of an oscillating arm, a link connected with the guide and arranged with its 30 opposite end adapted to slide on the arm, a pin on the end of the link, a ratchet-disk pivoted on the arm and formed with an annular flange having an opening adapted to admit the pin through the flange, and a pawl adapted to engage the teeth on the 35 ratchet to hold the pin under the flange when the arm is at rest and to rotate the disk when the arm is oscillated to cause the flange to ride over the pin.
25. In a winding machine, the combination with the winding-spindle and thread-guide, of an oscillating arm for reciprocating the guide, means to oscillate the arm, means to disconnect the arm from the oscillating means, means connecting said arm to reciprocate the guide therefrom, automatically operated means to shift the connecting-means from one end of the arm to the other to vary the operative effect of its 40 throw, and means to lock the arm at one extreme of its throw to provide for shifting the connecting-means manually into position adjacent the axis of the arm.
26. In a winding machine, the combination with the winding-spindle and thread- 45

guide, of an oscillating arm for reciprocating the guide, means to oscillate the arm, means to disconnect the arm from the oscillating means, means connecting said arm to reciprocate the guide therefrom, automatically operated means to shift the connecting-means from one end of the arm to the other to change the reciprocation of the guide from a minimum to a maximum traverse, and means to lock the arm at one extreme of its throw during the adjustment of the connecting-means, said locking means carried into operative position during the disconnection of the arm and released automatically when the arm is connected again with the oscillating means. 70

27. In a winding machine, the combination with a winding-spindle and thread-guide, of an oscillating arm, a connection between the guide and arm adapted to slide toward and away from the axis of the latter, and means operating automatically to engage said connection to retain it in position adjacent the axis of the arm when said connection is moved into such position on 75 the arm.

28. In a winding machine, the combination with a winding-spindle and thread-guide, of an oscillating arm, a connection between the guide and arm adapted to slide toward and away from the axis of the latter, means to retain the connection in position adjacent the axis of the arm, and means to automatically engage the retaining means with the connecting-means when the latter 80 is moved toward the axis of the arm.

29. In a winding machine, the combination with a winding-spindle and thread-guide, of an oscillating arm, a connection between the guide and arm adapted to be 85 shifted in relation to the axis of the latter, means automatically engageable with said connection to retain the latter when it is shifted to a point adjacent the axis of the arm, and means to release the retaining means at a predetermined point in the winding. 90

30. In a winding machine, the combination with a winding-spindle, and thread-guide, of an oscillating arm, a connection between the guide and arm adapted to be 95 shifted in relation to the axis of the latter, retaining-means automatically engageable with said connection when the latter is shifted to a point adjacent the axis of the 100 arm, and means operated by the oscillation of the arm to release the retaining-means after a predetermined number of oscillations. 110

31. In a winding machine, the combination with a winding-spindle and thread-guide, of an oscillating arm, a connection between the guide and arm adapted to be 115 shifted in relation to the axis of the latter, retaining-means automatically engageable 120 with the connecting-means when the latter is shifted to a point adjacent the axis of the arm, and means operated by the oscillation of the arm to release the retaining-means after a predetermined number of oscillations. 125

130

with said connection when the latter is shifted to a point adjacent the axis of the arm, means operated by the oscillation of the arm to release the retaining-means after a predetermined number of oscillations, and means to shift the connection to the end of the arm after its release by the retaining-means.

In testimony whereof we affix our signatures in presence of two witnesses.

ARTHUR I. HARVEY.
WILLIAM MARCROFT.
